(57) **CLAIM**

The ornamental design for an pair of headphones, as shown and described.

DESCRIPTION

FIG. 1 is a perspective front view of a right pair of headphones showing my new design;

FIG. 2 is a perspective rear view thereof;

FIG. 3 is a front view thereof;

FIG. 4 is a rear view thereof;

FIG. 5 is a left side view thereof;

FIG. 6 is a top view thereof;

FIG. 7 is a bottom view thereof;

FIG. 8 is a perspective front view of a left pair of headphones;

FIG. 9 is a perspective rear view thereof;

FIG. 10 is a front view thereof;

FIG. 11 is a rear view thereof;

FIG. 12 is a right side view thereof;

FIG. 13 is a top view thereof; and,

FIG. 14 is a bottom view thereof.

The broken lines shown in the drawings are included for the purpose of illustrating environmental structure and form no part of the claimed design.

1 Claim, 4 Drawing Sheets
